UNITED STATES PATENT OFFICE

CHARLES H. GLASS, OF HARTLEY, TEXAS

OIL PUMP

Application filed July 30, 1929. Serial No. 382,213.

This invention relates to an oil pump and container especially designed for use in transferring oils such as lubricating oils, from a drum or tank, to the crank casing of an automobile.

The primary object of the invention is to provide a device of this character which will transfer oil from a container to the crank casing of an automobile, eliminating any possibility of foreign matter such as dust, rain or snow, entering the oil.

Another object of the invention is to provide a device of this character which will facilitate the filling of crank casings by forcing the oil from the body portion of the device as distinguished from the usual method of allowing the oil to move by gravity into the crank casing.

A still further object of the invention is the provision of means for regulating the quantity of oil passing from the body portion of the device, so that the amount of oil may be accurately dispensed.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view of an oil pump constructed in accordance with the invention and showing the same as positioned for filling.

Figure 2 is a longitudinal sectional view through the pump.

Figure 3 is a sectional view taken on line 3-3 of Figure 2.

Figure 4 is a sectional view taken on line 4-4 of Figure 2.

Figure 5 is an enlarged longitudinal sectional view through the pipe that is positioned in the drum or tank containing the oil.

Figure 6 is an enlarged sectional view of the vent pipe of the tank.

Referring to the drawings in detail, the

pump comprises a cylindrical body portion 5 formed of translucent material, so that the operator may view the oil contained in the body portion of cylinder 5. Heads 6 and 7 respectively are positioned over the ends of the body portion 5 and fit against the gaskets 8 to provide a fluid tight connection between the ends of the body portion and the heads, there being provided rods 9 extended through openings in the heads for drawing the heads into close engagement with the gaskets.

The reference character 10 designates a hollow handle portion provided with a hand grip 11 at its outer end, the handle portion 10 being designed to receive the rack bar 12 to which the plunger 13 is secured. Cooperating with the rack bar 12 is a pinion 14 mounted on the shaft 15 that extends through the head 6, there being provided a crank handle 16 mounted on one end of the shaft 15, so that the shaft may be rotated to move the pinion over the rack bar 12 and cause the rack bar to move longitudinally of the handle portion 10, resulting in a relative movement of the plunger 13 to draw liquid into the body portion 5 to fill the body portion, and force the liquid from the body portion into the crank casing to be filled.

At one end of the rack bar 12 is a depending lug 17, which lug is adapted to be engaged by the sliding bolts 18 that are spring pressed and move through openings in the handle 10. Bell crank levers 19 connect with the sliding bolts 18, and have connection with the bars 20 that extend from the levers 21 which are pivotally supported adjacent to the grip 11, so that the operator may by moving the levers 21, withdraw the pins 18 to allow the rack bar 12 and plunger to move freely. It will also be seen that due to this construction, certain of the pins may be extended in the path of travel of the lug to restrict movement of the rack 12, so that only a predetermined quantity of oil will be dispensed.

The reference character 22 designates a discharge pipe to which the curved pipe 23 is connected, the curved pipe 23 having connection with the valve casing 24, in which the valve 25 moves, the valve 25 being oper-

ated by means of the bell crank lever 26, rod 27 and arm 28, the arm 28 being operated by pressure extended on the extension 29, by the thumb of the person gripping the member 11.

5 A spring 30 acts to return the valve to its normal closed position.

In order to facilitate the use of the device, a pipe such as indicated at 31 is positioned 10 in the drum or barrel containing the oil supply, the pipe being supplied with a valve chamber 32 at its upper end, in which the one-way valve 33 is positioned, the valve 33 acting to permit oil to be drawn through the 15 pipe 31, but prevent the oil from returning to the tank upon reverse movement of the plunger in the body portion 5.

Secured to the upper end of the valve housing 32 is a union 34 having a curved 20 upper surface 35 to receive the curved lower surface 36 of the valve casing 24. A vent pipe indicated at 37 has connection with the drum or supply tank, which in the present showing is indicated by the reference letter 25 A, the vent pipe being supplied with a cap 38 formed with openings to register with openings of the vent pipe, so that the cap 38 may be rotated to bring the openings thereof into alignment with the openings of the 30 pipe, when it is desired to remove oil from the drum or tank. The cap may be moved to close the openings to prevent foreign matter from entering the tank A when oil is not being drawn from the drum or tank A.

35 A drain valve 39 is in communication with the body portion and provides means whereby the contents of the body portion may be drained, should it be desired to clean the body portion.

40 In the operation of the device, the valve casing 24 is positioned on the union 34, in a manner as shown by Figure 1 of the drawings. The levers 21 are now operated to withdraw pins 18 from the handle 10, whereupon the handle 16 is operated to move the plunger 13 longitudinally of the body portion 5, and towards the handle 10, drawing liquid from the drum A into the body portion 5.

50 It is of course understood that prior to the operation of the plunger as described, the operator opens the valve 25 by exerting a pressure on the extension 29. After the body portion 5 has been filled, the valve 25 is 55 again opened and the pins 18 are withdrawn, whereupon the handle 16 is rotated in the opposite direction to force the liquid from the body portion 5 and into the crank casing of a motor vehicle to be filled.

60 Should it be desired to dispense one quart of oil, the lever 21 connected with the first pin, or pin nearest to the grip 11, is operated to move the pin out of the path of travel of the lug on the rack bar 12. As the handle 16 65 is rotated to force the oil from the body por-

tion, it is obvious that as the rack bar 12 moves a predetermined distance, the next pin 18 will contact with the lug of the rack bar 12 to prevent further operation of the rack bar and plunger and insure only one quart 70 of oil being forced from the body portion.

I claim:

In a device of the class described, a body portion, a hollow handle secured to the body portion, a rack bar operating through the 75 handle and extending into the body portion, a depending lug at one end of the rack bar, sliding bolts extending into the hollow handle and disposed in the path of travel of the lug, for restricting movement of the rack 80 bar, bell crank levers connected with the sliding bolts, bars connected with the bell crank levers, and levers connected with the last mentioned bars and disposed adjacent to the handle for operating the bars and sliding bolts 85 to move certain of the bolts to allow the rack bar to move through the handle, a plunger on one end of the rack bar, and means for moving the rack bar through the body portion.

In testimony that I claim the foregoing as my own, I have hereto affixed my signature.

CHARLES H. GLASS.
